Germany; vested in the Alien Property CustodianApplication August 23, 1939, Serial No. 291,610
In Germany August 27, 1938

6 Claims. (Cl. 61—8)

This invention relates to navigation locks, and more particularly to novel means for towing a ship through the lock.

In locks utilizing gates which are shiftable horizontally across the ship channel to provide the lock chamber, it has heretofore been regarded as difficult to provide a towing mechanism located below the top of the side-walls of the ship channel, that is in the side-wall itself, because such an arrangement would interfere with the operation of the horizontally shiftable lock gates whose top edges are located either above the surface of the lock walls, as for example, where a dike must be employed at one side of the lock, or, even where the top edge of the gate is flush with and exposed at the upper surface of the lock wall. Taking these factors into consideration, the present invention has in view a construction which eliminates the difficulties heretofore encountered by providing sectional articulated towing racks so constructed as to be uncoupled to provide in effect an intermediate element or section to which the ship is connected, and end sections which may be connected with and disconnected from said intermediate element as the vessel progresses through the lock structure whereby said sections may be separated and shifted so that the gates which form the lock chamber may be readily moved when desired without interference by any part of the towing rack. On the other hand, when the gates are retracted to permit movement of the vessel into and out of the lock chamber, a transfer track section carried by the gate effectively bridges the gap that would otherwise exist for insuring transfer of the rack means from one aligned track section to the other. Suitable propelling means are provided for the manipulation of the rack sections as the vessel progresses through the various stages of the lock and at the same time effectively tow the vessel properly through the ship channel.

With the foregoing general objects in view, other objects will appear as the description proceeds and the nature of the invention is better understood.

In the accompanying drawings:

Fig. 1 is a diagrammatic plan view of a lock installation according to the present invention.

Fig. 2 is a diagrammatic vertical sectional view taken through the ship channel showing the ship in the approach section with one of the lock gates retracted and the other closed.

Fig. 3 is a view similar to Fig. 2, showing the towing means advanced from the initial posi-

tion of Fig. 2, to move the ship into the intermediate lock chamber.

Fig. 4 is a view similar to Fig. 3, showing both of the lock gates closed after the ship has been elevated to the level required to leave the exit section of the lock.

Fig. 5 is also a vertical diagrammatic sectional view through the ship channel showing one of the gates closed and the other gate retracted to permit the ship to leave the lock chamber, the towing rack being shown in its farthest advanced position.

Fig. 6 is a vertical transverse sectional view taken at the location of one of the sliding gates and showing the gate in retracted position.

Fig. 7 is a detail vertical sectional view of the upper edge of one of the side walls of the ship channel illustrating the guideway or slot provided below the surface of the lock structure and also showing the track means for receiving the towing rack.

Fig. 8 is a fragmentary elevation of the upper corner of the gate having a transfer track section projecting therefrom and which is adapted to align with the main track section in the wall of the ship channel when the gate is retracted.

Fig. 9 is a detail vertical sectional view illustrating the enlarged guideway or slot respectively in the side-wall of the approach and exit ends of the ship channel and having therein double track sections which communicate with each other at one end to accommodate and receive two connected sections of the articulated rack when the latter is located at either the approach or exit ends of the structure.

Fig. 10 is a diagrammatic plan view illustrating a modification of the towing means wherein a towing rack section is connected with a comparatively heavy carriage connected with ship engaging means.

Fig. 11 is a detail vertical sectional view of the modified guideway or slot in the side wall of the ship channel as used in Fig. 10.

Fig. 12 is a fragmentary vertical sectional view of the upper corner of the lock gate shown in Fig. 10.

Fig. 13 is a detail view illustrating a form of rack and driving means therefor according to Figs. 1—9 inclusive.

Fig. 14 is a detail horizontal cross section of the rack of Fig. 13 taken at the point where one of the ship stays connects therewith, and also showing a portion of the side of the vessel illustrating how the stays are connected to the ship. Similar reference characters designate corre-

sponding parts throughout the several figures of the drawings.

In the following description, it will be understood that the entire structure is regarded as a navigation lock, and for the purposes of description, the same includes an intermediate lock chamber and approach and exit sections therefor. The ship will be regarded as proceeding from left to right in Fig. 1, that is, from a low water level to a higher water level, but, on the other hand, if it is desired to drop the ship from the higher water level to a lower water level, the exit section becomes the approach section and the operation of the towing mechanism will be just the reverse of that about to be described.

In Fig. 1, the entrance to the lock is designated generally as 1 and is formed by the walls 2 and 3 of the approach section. The lock chamber 4 is formed by the sliding gates 5 and 6. The exit portion of the ship channel is designated as 7, and is defined by the spaced walls 8 and 9. At one end of the lock structure, a dike 10—11 may be provided. The horizontally shiftable or slideable gate 5 is located at the said dikes and its upper edge is preferably flush with the top of the dike. On the other hand, the top of the sliding gate 6 may be flush with the upper surface of the walls of the ship channel consisting of the sections 1, 4 and 7.

Below the upper surface of one of the walls forming the ship channel, there is provided a slot or guideway 13. This slot or guideway is, of course, continuous except for the interruptions occurring at the location of the sliding gates. The said guideway 13 is intended to receive suitable upper and lower track sections 13^a, which are longitudinally coextensive with the guideway or slot except where the sliding gates occur. The guideway 13 is preferably of greater depth at the approach section 1 and exit section 7 than it is in the intermediate section or lock chamber 4. The purpose of this greater depth is to accommodate a lower track section 13^b (see Fig. 9) which communicates at its outer end with the upper or main track section 13^a so as to permit the rack to double back upon itself at the entrance and exit sections of the lock, as will hereinafter more fully appear.

The track sections 13^a and 13^b are intended to receive an articulated rack which preferably consists of the end section 14, the intermediate section 22 and the end section 16. The said sections 14 and 16 are intended to be connected and disconnected at their inner ends with the adjacent ends of the intermediate rack section 22, said section 22 constituting in effect the rack section which stays with the ship 18 during its entire progress through the lock structure. The purpose of making the section 22 detachable from the end sections is to permit the end sections to be moved clear of the positions of the gates 5 and 6 in order that they may be horizontally shifted to closing position when required.

The rack sections 14, 16 and 22 may be of any construction suitable for the purpose. However, as will be observed from Figs. 13 and 14, said racks preferably consist of a plurality of links x connected by cross members y which are so spaced as to permit the power driven driving gear 15 to engage therewith. The said links at their point of pivotal connection with each other are provided with rollers or wheels z which ride in the track sections 13^a and 13^b. It will, of course, be understood from Figs. 1-5 that the power driven gear device 15 is located at one of

the end sections of the lock, and a similar power driven device 17 is associated with the other end section of the lock. When the ship 18 enters the approach section 1, the power device 15 will engage the intermediate rack section 22 which is connected to the ship by suitable stay elements 19. The said stay elements 19 may also be of any construction suitable for the purpose. By way of illustration, Fig. 14 shows the stay elements 19 which have their inner ends 19^a connected to a rod or bar, which is in fact an extension of one of the cross rods y of the chain and terminates in an eye 19^b. The said inner ends 19^a may be bolted or otherwise detachably secured to 19^b. The opposite ends of each stay are preferably provided with vertical hollow tubular guide portions 19^c which are intended to slidably receive the guides 19^d carried by the side of the ship. The upper ends of these guides may be fitted to the deck of the vessel as shown at 19^e by any suitable form of clamping means, and the lower ends of said guides may be secured to the side of the vessel by fitting in the eyes or the tubular brackets 19^f carried by the hull. It will, of course, be understood that the rack section 22 is connected with the rack section 14, which, while the ship is in the approach section 1, lies within the lower track section 13^b, as will appear from Fig. 2, from which it will be seen that the gate 5 is in its retracted position. When the gate 5 is so retracted, the transfer track section 13^c (Fig. 8) projecting from the upper corner of the gate will align with the track sections 13^a so that the towing rack may be shifted from the approach section 1 toward the lock chamber 4. This shifting is accomplished by the power driven device 15 engaging the leading end of the towing rack 22 which is connected with the ship. The power driven device pulls the rack section 22 to tow the ship from the approach section into the lock chamber, and when the rear end of section 22 has passed the point of the power driven apparatus 15, the rack section 14 will continue to push the ship into the lock chamber. When the ship has advanced to the position indicated at 21 (Fig. 3), the rack section 14 may be disconnected from the rack section 22 and before the gate 5 is closed the power driven device 15 may be operated to move the section 14 back into the track section 13^a of the approach section. The gate 5 may then be closed (Fig. 4) and the lock chamber 4 may then be filled with water to a level corresponding with the water level in the exit sections 7. This is also indicated in Fig. 4. The gate 5 remains closed and the gate 6 may then be opened so that the rack section 16 of the exit section 7 may be manipulated by the power driven device 17 to permit its inner end to be connected with the intermediate rack section 22 connected to the ship. In order to accomplish this shifting of the section 16, across the position of the gate 6, it will, of course, be understood that the gate 6 is provided with a transfer track section which is a duplicate of the transfer track section 13^c carried by the gate 5, as shown in Fig. 8.

After the towing rack section 16 has been connected with the rack section 22, the power driven device 17 is again operated so as to pull the connected rack sections 16 and 22 in the trackway 13^a to the position shown in Fig. 5. From this figure, it will be apparent that the rack section 16 is fed from the upper into the lower track section 13^b (Fig. 9) of the exit section, and the ship connected intermediate section

22 is still in engagement with the power device 17. When the ship 18 is in the position 22^a of the exit section (Fig. 5), it may be disconnected from the intermediate towing section 22 and proceed under its own power.

The rack sections 16 and 22 may be left connected as shown at the right hand end of Fig. 5 if desired, to receive a ship which may desire to proceed in the opposite direction. On the other hand, if another ship enters the lock and intends to proceed in the same direction as the ship 18, the towing rack sections 16 and 22 are uncoupled or disconnected and the section 22 is moved toward the approach section 1 by the power mechanism 17 and the towing section 14, in its turn, may be moved by the power mechanism 15 to connect with the opposite end of the section 22 and bring it back to the position shown at the left-hand end of Fig. 2.

In the modification of the invention shown in Figs. 10, 11 and 12, the essential difference over the construction shown in Figs. 1 to 9, is that only two articulated rack sections need be employed, but the equivalent of the third rack section is present in the form of carriages which may be connected with the ship and are capable of being coupled and uncoupled with the two articulated track sections, the said carriages operating in enlarged portions of the slots or guideways, in their own trackways, in such enlarged portions as will presently appear more in detail.

Fig. 10 is a diagrammatic plan view, illustrating a horizontally shiftable gate 23 adapted to be housed in a gate chamber 24, the said gate when projected across the ship channel being adapted to separate the lock chamber 25 from the approach chamber 26. The ship 27 is anchored to the travelling towing carriages 28 by the aid of fastening means 30. The said towing carriages 28 and 29 which correspond in function to the intermediate rack section 22, are located in the enlarged guideway 31 in one of the side walls of the ship channel and are provided with top, bottom and side guide rollers 32 intended to engage suitable track elements 32^a (see Fig. 11). In the rear of the enlarged guideway, 31, the side wall of the ship channel is provided with a guideway 13^d which receives the articulated rack section 33 adapted to travel in the tracks 34, said rack section comprising links and cross members mounted on rollers for engaging the tracks substantially in the same manner as shown in Figs. 13 and 14. The rack section 33 is adapted to be operated by a power device 35 shown in Fig. 10 in the same manner as the corresponding end sections of the rack in Figs. 1 to 5, inclusive.

The gate 23, as shown in Fig. 12, is provided at its upper outer portion with an enlarged horizontal recess or cavity located below the surface of the gate and identified as 36, which permits the elongated towing carriages 28 and 29 to clear the gate when in its retracted position, as shown in Fig. 10. The gate is also provided inwardly of the recess 36 with a smaller recess 36^a which houses the transfer track sections 37 intended to align with the track sections 34 to permit the articulated rack section 33 to be guided across the gate in its retracted position, and also to permit the rack section to move the towing carriages 28 and 29 coupled thereto to properly tow the ship through the various sections or stages of the lock.

As will be apparent from Fig. 10, the carriages 28 and 29 may be coupled and uncoupled with the

selected articulated rack section by means of the coupling device diagrammatically indicated at 38 and 39.

When the gate 23 is closed, in the event of high water, provision must be made to prevent water passing from one side of the gate to the other through the recess 36. This is accomplished by a sluice 40 (Fig. 12) which is moved within the gate between the separated ends of the transfer track sections 37 carried by the gate by a propelling device 41 in such a manner, that the recess 36 can be closed when the gate is closed, as illustrated in dotted lines in Fig. 10. The propelling device 41 preferably includes a gear 42 carried by a motor driven shaft; the said gear engaging with a rack 43 carried by the rear end of the sluice 40.

In the construction shown in Figs. 10 and 12, it will be understood that when the ship 27 enters the approach section 26, the towing carriages 28 and 29 are coupled to the end rack section 33 and are also connected to the ship by the fastening means 30. As the power device 35 propels the articulated rack 33, the carriages 28 and 29 will move with it, and assuming that the gate 23 is open, as shown in Fig. 10, the ship will advance from the approach section 26 to the lock chamber 25. With the ship in this position (Fig. 10), the carriages 28 and 29 may be uncoupled from the articulated rack 33 by releasing the coupling devices 38 and 39 which may be in the form of an arm extending inwardly from the rear side of the carriage and an arm extending outwardly from the rack, said arms being at different elevations so that they may pass each other and each having an eye adapted to register with the other to receive a coupling pin as shown in Fig. 11. Since the carriages 28 and 29 travel in their own tracks 32^a and likewise the articulated rack 33 travels in its own trackway, the power device 35 may be operated to pull the articulated rack 33 fully back into the approach section, leaving the carriages 28 and 29 in the positions which they occupy when detached from the rack. It will, of course, be understood that after the vessel 27 is moved into the lock chamber 25 and the articulated rack 33 is disconnected from the carriages, the lock gate 23 will be moved to closed position. In other words, the rack 33 must be moved out of the way before the gate 23 can be closed.

After the lock chamber 25 has been filled with water to the desired level to elevate the ship, the outlet gate of the lock chamber may be opened and the articulated rack section (not shown) corresponding to the rack section 16, may be moved from the exit section into the lock chamber section on the tracks 37 and then coupled at 38 and 39 with the exit rack section. The exit rack section may then be moved by its associated power device to tow the ship out of the approach section in the same manner as described in connection with Figs. 1-9.

From the foregoing it will be apparent that the present invention contemplates a navigation lock wherein the towing means is located below the surface of the lock structure and essentially consists of a plurality of shiftable sections which may be connected and disconnected to progressively moving the ship through the ship channel or canal.

I claim:

1. A navigation lock, including in combination, a side wall of the ship channel having a guideway therein below the top edge of the wall, sliding gates retractible and projectible from said side wall having the guideway and slidably in

gate chambers interrupting said guideway, track means in said guideway and also interrupted at the gate chambers, a transfer track section carried by each gate, and ship towing means shiftable in the track means of said guideway and the transfer track section of a gate when the latter is opened, said towing means comprising a plurality of detachable sections adapted to be uncoupled and separated, thereby to be moved clear of the gates and permit a selected gate to be closed.

2. A navigation lock according to claim 1, wherein the towing means consists of two articulated end rack sections and a shiftable intermediate section detachably and selectively connectable with either end section, and means for connecting the intermediate section with a ship.

3. A navigation lock according to claim 1, wherein the towing consists of two end rack sections and an intermediate section slidable in said track means and detachably and selectively connectable with either end section, means for connecting the intermediate section with a ship, and separate driving means for propelling each end section and the intermediate section when connected thereto.

4. A navigation lock according to claim 1, wherein the edge of the gate carrying the transfer track section is also provided with a recess to register with said guideway, and a sluice arranged in said gate and adapted to close said recess in the case of high water.

5. A navigation lock comprising a ship channel having approach and exit sections on opposite sides of a lock chamber, a pair of horizontally slidable gates defining the lock chamber, a continuous guideway formed in a wall of the ship channel below the surface of said wall, the ends of said guideway at the approach and exit sec-

tions being of greater depth than the portion of the guideway in the lock chamber, track means in the guideway interrupted at the location of said gates, said track means in the approach and exit ends of the ship channel comprising upper and lower communicating track sections, a towing rack consisting of end and intermediate sections adapted to be coupled and uncoupled and shiftable in said track means, means for connecting the intermediate section of said rack with a ship, power devices associated with said track means respectively adjacent the end of the approach section and the beginning of the exit section and having propelling engagement with said track sections, a transfer track section carried by the gate and adapted to align with the track means in said guideways when the gate is retracted to bridge the aforesaid interruption in said track means.

10 6. A navigation lock, including in combination, a side wall of the ship channel having a guideway therein below the top edge of said wall, said guideway including a relatively wide outer portion having a trackway therein and a relatively narrow inner portion also having a trackway therein, sliding gates retractable and projectible from said side wall having a guideway and slideable from chambers interrupting said guideway, said gates having recesses in one edge corresponding to the said guideway, one of said recesses including a transfer track section, articulated towing rack sections shiftable in the trackways of the narrow inner portions of said guideway, separate power driven means for shifting said rack sections, ship anchoring carriages shiftable in the trackway arranged in the wide outer portion of the guideway, and means for detachably connecting the carriages to a selected rack section.

HEINRICH BREITWIESER.
